(57) **CLAIM**

The ornamental design for a refrigerator, as shown and described.

DESCRIPTION

1. Refrigerator
- 1.1 is a perspective view of a refrigerator showing my new design;
- 1.2 is a front elevation view thereof;
- 1.3 is a rear elevation view thereof;
- 1.4 is a left-side elevation view thereof;
- 1.5 is a right-side elevation view thereof;
- 1.6 is a top plan view thereof;
- 1.7 is a bottom plan view thereof;
- 1.8 is a perspective view thereof, wherein each outer door is in an opened position;
- 1.9 is a front view thereof, wherein each outer door is in an opened position;
- 1.10 is a right-side view thereof, wherein each outer door is in an opened position;
- 1.11 is a top plan view thereof, wherein each outer door is in an opened position;
- 1.12 is a perspective view thereof, wherein each of the inner and outer doors is in an opened position;
- 1.13 is a front view thereof, wherein each of the inner and outer doors is in an opened position;
- 1.14 is a right-side view thereof, wherein each of the inner and outer doors is in an opened position;
- 1.15 is a top plan view thereof, wherein each of the inner and outer doors is in an opened position; and
- 1.16 is a perspective view thereof, wherein the inside of each outer door is seen through a 'see-through' type of window.

(Continued)

The broken lines shown are included for the purpose of illustrating unclaimed portions of the refrigerator and form no part of the claimed design.

1 Claim, 15 Drawing Sheets
